UNITED STATES PATENT OFFICE

LUDWIG REICHOLD, OF WINSTED, CONNECTICUT, ASSIGNOR TO THE FITZGERALD MANUFACTURING COMPANY, OF TORRINGTON, CONNECTICUT, A CORPORATION OF CONNECTICUT

CONTROL SWITCH PARTICULARLY FOR ELECTRIC SADIRONS AND SIMILAR DEVICES

Application filed December 23, 1929. Serial No. 416,126.

This invention relates to improvements in thermostatically controlled switches and is more particularly intended for employment on electric sad-irons or similar devices in which it is desired to maintain the device at a substantially constant temperature, with the possibility of varying this temperature to a higher or lower degree.

One of the particular features of this invention is the provision of a switch which is quickly made or broken at a predetermined variable point, the contacts being so actuated that they are fixed in the "made" or "broken" position, and move between these positions rapidly and without delay.

Another feature of the invention is to construct a switch of this type with the employment of a double toggle system, these toggles being subjected to strong and weak spring effects, whereby one toggle system causes the switch contacts to remain in either "made" or "broken" position, while the other toggle causes the rapid shifting of the contacts between "made" and "broken" positions.

A further feature of the invention is the provision of a structure in which the spring effects are maintained at definite ratios, so that one toggle is subjected to a strong spring effect and the other to a weak spring effect: and more particularly to establish these ratios at definite values by the employment of lever arms.

Still another feature of this invention is to obtain these spring effects upon both toggles by the employment of a single spring, and more particularly to so construct and arrange the mechanisms that this spring is maintained in a position in which it is substantially protected from heating by the device, whereby its temper and springiness are preserved.

Still a further feature of the invention is the provision of a peculiar type of thermostatic bar control for the switch elements, whereby the thermostatically produced movement is regulated and adjusted as desired by the operator of the iron, so that the switch is quickly made or broken at desired

different temperatures, whereby a constant temperature is maintained in the device.

With these and other objects in view, as will appear in the course of the following specification and claims, the switch and associated parts will now be described in an illustrative form in connection with a sad-iron, but it will be understood that this is by way of illustration and not of limitation as to the application of the invention and its several features in the arts.

In these drawings:

Fig. 1 is a longitudinal sectional view substantially on line 1—1 of Fig. 2.

Fig. 2 is a corresponding horizontal view 65 with handle removed and the cover or skirt broken away, and with other parts in dotted lines to indicate their relative positions.

Fig. 3 is a diagrammatic view showing the relationship of the moving parts, with 70 the switch plate omitted for greater clearness.

Fig. 4 is a similar view of the thermostatic plate and control members.

Fig. 5 is a transverse sectional view substantially on line 5—5 of Fig. 2.

Fig. 6 is a perspective view showing in detail the construction of the cam control shaft.

Fig. 7 is a similar detailed perspective 80 view of a lever control arm.

According to the present invention, a thermostatically actuated member which controls the position of a first toggle linkage, this toggle linkage being free to move with respect to a second toggle linkage between definite limiting positions. At these limiting positions, the first toggle linkage causes a movement of the second toggle linkage between definite end positions: so that circuit closing elements connected to the second toggle linkage are held or moved rapidly and positively between open and closed position by the action of the second toggle linkage, while the first toggle linkage serves as a trigger to direct and control this movement. By controlling the point at which the trigger action begins, a thermostatic switch is provided with a regulatable point 100

of cut-off or make-and-break, so that the temperature of the entire device is closely and definitely regulated: and in a particular illustration, this is effected by a direct control of the thermostatic element itself.

In the drawings, the invention has been illustrated as applied to an electric iron having the base or shoe member 10 which supports the heating element 11 directly in contact therewith, it being understood that this element is assembled as usual of the insulating plates enclosing the heating wires. The heating element is illustrated as of flat form and is closely pressed against the shoe by a clamping block 12 which has cavities 13, 14 and 15 formed therein. An apron or skirt 16 encloses the clamping block and parts located thereon and fits tightly down upon the shoe, and serves to establish a heat insulating air jacket with respect to the hot inner members, and provides a smooth external surface for the entire iron. The handle strap 17 rests upon dished washers 18 supported upon the skirt 16 and is provided with a handle of any desired shape (not shown). Stud screws having the polygonal section 19 by which the lower threaded ends 20 may be screwed into the shoe 10, serve to clamp the clamping block 12, the heating element 11 and the shoe 10 tightly together. The upper end of each of these screws 19 is passed through a corresponding aperture in the skirt, through the respective washer 18 and a hole in the handle strap 17, and receives a cap 21 which serves in turn to clamp the handle and washer 18 tightly down upon the skirt 16, so that in effect the screws 19 serve to clamp all parts of the iron rigidly together: and conversely, by separating and removing these screws, the several parts may be removed one from another for inspection and repair of the iron. The plug protecting sleeve 22 has a rearwardly bent curl 23 which acts in conjunction with the heel guard 24 to form a support for the iron when turned over to rest on these members, the shoe 10 then being out of contact with the ironing board or material of the iron, and this position constituting an easy and immediately available rest for the iron when hot. It will particularly be noted that the heel guard 24 is supported from the apron or skirt 16 and is of sheet metal with a space between its upper and lower members, the lower member having an aperture 25 formed therein for ventilating and maintaining this heel guard cool.

The clamping block 12 receives a switch plate 26 which is secured thereto by screws 27. Beneath this plate and within the cavity 13 is provided a thermostatic bar 28 which may be of the usual bi-metallic or other type and is secured by a screw 29 to the clamping block 12. The free end of the

thermostatic bar 28 carries an end plate 30 having a notch 31 in its upper edge. As the thermostatic bar becomes heated, it moves the end plate 30 relatively outward in Figs. 2, 3 and 4.

70

The electric circuit of the illustrated iron extends from one plug prong 32 which is supported on an insulating bridge 33 by a band conductor 34 to one terminal of the heating element 11, with a return by a similar band conductor 35 from the other end of the heating element to a switch terminal plate 36 which is securely riveted to, but insulated from, the switch plate 26. A similar switch terminal plate 37 is riveted to, but likewise insulated from, this switch plate 26; and in turn is connected by a conductor 38 to the other prong 39 of the insulating bridge 33. Each of the switch terminal plates 36, 37 is provided with an upturned end 40 (Fig. 1) having a contact 41, 42 thereon to engage with the similar contacts 43, 44 carried by a floating bridge member 45 but insulated therefrom, the individual contact points 43, 44 being connected by a conductive web 46 (Fig. 3).

105

110

115

The switch plate 26 has a slot 47 therein to receive a slider 48 which has a long foot 49 to prevent it from being pulled upward through the slot 47, and for guiding it for movement back and forth in this slot. The upper portion of the slider 48 has two apertures 50 and 51 therein. The switch plate likewise has two upstanding studs 52, 53 therein, each of which has a V-shaped notch for the reception of the sharp ends of respective toggle members 54, 55, which extend through the respective apertures 50, 51 of the slider 48 and have V-shaped grooves in their free ends to receive the ends of the second toggle link members 56, 57, which are formed of thinner material and have narrower ends such as 58 (Fig. 5) to rest within the channel-shaped pressure arms 59, 60, while the shoulders presented by the respective members 54, 55 bear against V-shaped notches 61 provided in these members. It will be noted that the effective width of the aperture 50 is less than the effective width of the aperture 51: and that in effect the toggle linkage 54, 57 moves at all times with the slider 48, while the toggle linkage 55, 56 is free of this slider 48 so that it may move away from the corresponding wall of its aperture 51 when the slider 48 is in one position, until the toggle linkage 55, 56 has slightly passed its position of dead center, and is therefore capable of immediately snapping to its other end position, and therewith carrying the slider 48 along. The slider 48 has an extending end 62 which passes through an aperture of the bridge 45 and has clenched claws to hold the rocking bridge 45 in position, while permitting it to rock laterally slightly in all di-

rections whereby to accommodate itself to the contacts 41, 42 as necessitated by the position of the parts.

The toggle link 55 has a spur 63 extending into the notch 31 of the end plate 30 of the thermostatic bar 28, being somewhat thinner than the size of this aperture, so that as the end plate 30 forces the spur 63 in one direction and thereby also the first toggle linkage 55, 56, it causes this first linkage to come into contact with the slider 48 and thereby move it in one direction, the spur 63 being permitted a slight free movement in this slot of sufficient degree so that the bridge 45, 15 and contact points 43, 44 will quickly and positively make or break the electrical circuit.

The lever arms 59, 60 are pivotally mounted on studs 64, 65 upstanding from the switch plate 26: it being preferred to provide sleeves 66 about the posts and to secure these sleeves in position by set screws 67 whereby to support the lever arms 59, 60 away from the switch plate 26. Extensions 25 68, 69 are secured to the lever arms 59, 60 as by welding and have their rearward ends bent inwardly and then outwardly to provide the end pieces 70, 71 with apertures therein to receive the outturned ends of the 30 coil spring 72 which is located wholly within the heel guard 24 and outside of the heat insulating apron 16, where it is least exposed to heating from the iron. It is preferred to provide a guide member 73 to support the 35 spring 72 and hold it intermediate the upper and lower plates of the heel guard 24. It will be noted that the ends 70, 71 pass outward through slots 74 in the skirt 16.

The thermostatic bar 28 bears against a 40 cam 80 formed on a shaft 81 having the bearing pin 82 at the bottom thereof to be guided in the clamping block 12. The upper end of this shaft is provided with a portion 83 of irregular section to receive a handle 84 45 with a knob 85 therein. The upper end of the shaft 81 has screw threads 83a to receive a cap 84a which holds the handle 84 rigidly to the shaft. As the shaft is rocked, the cam bears more or less against the thermostatic bar (compare Figs. 3 and 4) so that a given bending of the bar in consequence of its heating will produce a lesser or greater movement of the end plate 30 thereof. For example, in Fig. 3, the pressure of the cam 50 55 80 against the thermostatic bar is practically eliminated at its "cold" position, so that the bar swings substantially from its securing screw 29 and therefore the plate 30 makes a considerable movement, and soon operates the spur 63 to cause a shifting of the switch and thereby an opening of the circuit: and, in other words, the iron is open-circuited at a relatively low temperature. It will be noted that the position of the handle 84 60 65 and knob 85 of Fig. 3 corresponds to the

position shown in dotted lines in Fig. 2, in which the handle is near the letters "LOW" shown in dotted lines in Fig. 2. On the other hand, if the shaft 81 is rocked so that the cam 80 bears more against the thermostatic bar 28, as in Fig. 4, the bar will cause a lesser movement of the end plate 30 for a given temperature, and hence a greater temperature will be necessary to move the spur 63 sufficiently to cause a snapping movement 75 of the first toggle linkage 55, 56 and thereby provoke an opening of the circuit; in other words, the iron will operate at a higher temperature, and the handle 84 must have been moved for this purpose in a clockwise direction about the axis of the shaft 81, i. e., further toward the position shown by the dotted letters "HIGH" in Fig. 2.

It will particularly be noted that the lever arm from the pivot 64 to the V-notches 61 of the lever arm 59, is less than the corresponding arm from the pivot 65 to the notches 61 of the lever arm 60: and on the contrary the lever arm from the pivot 64 to the engaging point at the end of the extended arm 70 is greater than the corresponding distance from the pivot 65 to the engaging portion of the corresponding end 71: so that by the employment of a single spring 72, a much greater endwise springy 95 compression is exerted upon the first toggle linkage 55, 56 than upon the second toggle linkage 54, 57. In other words, the snapping effect of the first toggle linkage 55, 56 is accomplished with much greater energy 100 than that of the second toggle linkage 54, 57, and this effect is wholly independent of the actual force exerted by the single spring 72, and is a consequence of the lever ratios 105 of the two systems.

In operation, the current having been turned on the device, the heating element 11 causes the several parts to rise in temperature until the thermostatic bar 28 moves through a definite arc, the temperature at 110 which this arc is completed being determined by the prevailing position of the cam 80 as regulated by the shaft 81 and handle 84 and as maintained by the spring pressure plate 86 which is clamped between the handle strap 17 and one of the washers 18, and has a downward bow to exert a frictional pressure on the handle 84 and thus to hold this handle in the set position.

It will be understood that while the iron 115 is cold the parts are in the position of Fig. 2. When the plate 30 moves through this arc angle, at first the plate moves until the width of the notch 31 is taken up, and thereafter the end plate 30 acts upon the spur 63 to rock the corresponding toggle linkage 55, 56 so that the joint between the two toggle elements moves relatively toward the left, but for the moment without contact with the slider 48, in consequence of the 120 125 130

width of the aperture 51. The relative length of the slider 48 and the slot 47 is so calculated that just at or shortly before the said first toggle linkage 55, 56 comes into contact with the slider 48, the toggle linkage has passed its position of dead center; and no longer exerts an outward force against the lever arm 59 and thereby against the spring 72: but now the spring delivers its energy through this lever arm 59 and causes the first toggle linkage 55, 56 to rapidly snap and move its center joint toward the left, carrying the slider 48 therewith and thus dragging the contacts 41, 43 and 42, 44 apart and breaking the circuit. During the time that the first toggle linkage 55, 56 has been moving independently of the slider 48, this slider has been held in closed position as shown in Fig. 2, by the action of the second toggle linkage 54, 57 which, however, is subjected to a much smaller endwise spring compression by reason of the differing lever ratios of the arms 59, 68 with respect to the arms 60, 69: the snapping movement of the first toggle links 55, 56 is therefore sufficient to rapidly and immediately drag the contacts apart, thus securing a proper opening of the circuit to the iron. The parts are then in the position shown in Fig. 3, the lever arms 59, 60 having moved from approximately the full line position to that shown in dotted lines and back again during the course of the operation just described, while the thermostatic bar has moved from the dotted line position to the full line position.

As the iron cools off, the thermostatic bar 28 moves from the position shown in full lines to that shown in dotted lines in Fig. 3, at first freely by reason of the notch 31, and then engages the spur 63 and moves the first toggle linkage 55, 56 so that its connecting joint travels toward the right in Fig. 3, again moving freely for the first part of its movement by reason of the width of the aperture 51. The second toggle linkage 54, 57 meanwhile holds the slider 48 against movement and keeps the circuit open at the contacts 41, 43 and 42, 44. Just at or after the time that the first toggle linkage 55, 56 comes to dead center, the elements of this toggle linkage come into contact with the slider 48, and cause this slider to be snapped quickly and immediately toward the right, thus quickly closing the circuit and the contacts. For the reasons above stated, the endwise compression of the second toggle linkage 54, 57 is less than the endwise compression of the first toggle linkage 55, 56, and therefore the first toggle linkage entirely controls the opening and closing movement, while the second toggle linkage 54, 57 holds the parts either in open or in closed position.

65 In order to prevent sticking or binding of

the parts if any rusting or corrosion should occur in the device, the apertures 50, 51 are preferably formed of greater width than is necessary, and the walls are provided with spurs 90: and the studs 52, 53 are provided with base flanges 91 to support the toggle linkage 54, 55 away from the switch plate 26, thus acting in conjunction with the supporting effects of the lever arms 59, 60 upon the toggle links 56, 57, so that the toggle linkages maintain themselves in position: and by reason of the engagement of the toggle links 54, 55 with the slider 48, the parts are held firmly in position and subjected to little or no wear. It is preferred to form notches 92 in the upper edge of the toggle links 54, 55, to prevent the slider 48 from tilting with respect to its plane. It is obvious that the parts may be easily and quickly separated one from another by compressing the arm extensions 68, 69 together, whereby the several elements of the toggle linkage may be easily freed from their positions, and inspected or replaced as needed.

It is obvious that the invention is not limited to the illustrative example shown, but that it may be constructed and employed in many ways within the scope of the appended claims.

What I claim as new and desire to secure by Letters Patent is:

1. In a device of the class described, a switch having fixed and movable contacts, first and second toggle linkages, means to produce spring effects upon the toggle linkages to move the same into and hold the same in end positions, said second toggle linkage being connected to the movable contacts to hold the same in open and closed positions, and means connecting said first and second toggle linkages whereby the said first linkage may move the said second linkage between end positions, said first toggle linkage having lost motion with respect to said second toggle linkage.

2. In a device as set forth in claim 1, a pair of independent pivoted lever arms, each of said arms establishing an end pivotal point for a corresponding toggle linkage, and a single spring operating upon both said lever arms to produce the spring effect upon both said linkages.

3. In a device as set forth in claim 1, the provision of a pair of independent lever arms and spring means to actuate said arms, one of said lever arms producing a spring effect on said first linkage and the other lever arm producing a spring effect on said second linkage, the lever ratios of said first spring arm producing a greater pressure upon said first linkage than the lever ratios of said second spring arm produces on said second linkage.

4. In a device as set forth in claim 1, the provision of lever arms to operate upon the

5 toggles to establish the spring effect thereon, and a spring to actuate said toggle arms, a heat insulating skirt surrounding the heating element of said device, said lever arms 5 extending outside of said skirt, said spring being located outside of said skirt whereby it is protected against loss of temper by heating from said element.

5. In a device of the class described, a 10 switch plate, fixed and movable switch contacts, said fixed contacts being supported on but insulated from said plate, said plate having a slot therein, a slider movable in said slot, a bridge loosely carried by said slider and 15 supporting said movable contacts to guide them into and out of conductive relationship with said fixed contacts, a toggle linkage to hold said slider in end positions in which the circuit is made or broken by said contacts, and thermostatically controlled means 20 to actuate said slider, said means including lost motion devices and devices to quickly move said toggle linkage between its end positions following the operation of said 25 lost motion devices.

6. In a device of the class described, a 30 thermostatically actuated bar, a switch including fixed and movable elements, a first and a second toggle linkage, said second 35 toggle linkage being connected to said movable elements to hold the same in circuit opening and circuit closing positions, said first toggle linkage having a lost motion connection with said second toggle linkage and 40 a lost motion connection with said bar, whereby the movement of said bar causes after the absorption of said lost motions a quick movement of said second toggle linkage between its end positions.

45 7. In a device of the class described, a switch having fixed and movable contacts, a first and a second toggle linkage, means to product spring effects upon said toggle linkages, the effect upon said first toggle linkage being greater than the effect upon said second toggle linkage, said second toggle linkage being connected to said movable contacts to hold the same in circuit opening and circuit closing positions, and a lost motion 50 connection between said first and said second toggle linkages whereby said first toggle linkage may move to a position approximating the dead center position without movement of said second toggle linkage and 55 thereafter will be snapped by its spring effect means to an opposite end position and thereby move said second toggle linkage to the corresponding end position.

8. In a device of the class described, a 60 frame, a thermostatically actuated bar rigidly connected at one end to said frame, a pair of toggle links having a pivotal connection at their adjacent ends, switch means operated by the movement of said adjacent ends, 65 said bar operating upon said links to move

them toward one end position when the bar is heated and toward the other end position when the bar is cooled, and means for varying the movement of said bar including a cam acting upon the bar intermediate its length and a handle for regulating the position of the cam, whereby to predetermine the temperature at which the toggle links are brought to the dead point by said bar upon movement of the latter.

9. In a device of the class described, a 70 block having a cavity therein, a switch plate closing said cavity, a thermostatically actuated bar located in said cavity, a regulating shaft journaled in said block and said plate, an enlarged portion on said shaft forming a retaining means to prevent axial movement of said shaft, said enlarged portion also forming a cam to cooperate with said thermostatically actuated bar to regulate the movement of said bar at predetermined temperatures, and means to hold said clamping block and switch plate together.

10. In a device of the class described, a 75 switch having fixed and movable contacts, a first and a second toggle linkage, said second toggle linkage being connected to said movable contacts and being adapted to move to small distances on either side of its dead center position whereby to hold the movable contacts in open or closed positions with respect to said fixed contacts, said first toggle linkage having a lost motion connection to said second toggle linkage so that said first toggle linkage moves a greater distance 80 on either side of its dead center, and means to establish spring effects upon said toggle linkages, the spring effect upon said first toggle linkage being greater than that upon said second toggle linkage, so that said first toggle linkage causes a rapid movement of 85 said second toggle linkage between its end positions.

11. In a device as set forth in claim 10, the provision of a single spring and lever arms connecting said spring, the lever ratios of said arms producing a greater spring effect upon said first toggle linkage than upon said second toggle linkage.

In testimony whereof, I affix my signature. 110
LUDWIG REICHOLD.
